UNITED STATES PATENT OFFICE.

CLYDE C. FARMER, OF PITTSBURGH, PENNSYLVANIA, ASSIGNOR TO THE WESTINGHOUSE AIR BRAKE COMPANY, OF WILMERDING, PENNSYLVANIA, A CORPORATION OF PENNSYLVANIA.

ANGLE-COCK HANDLE.

1,387,971.

Specification of Letters Patent. Patented Aug. 16, 1921.

Application filed October 15, 1919. Serial No. 330,786.

To all whom it may concern:

Be it known that I, CLYDE C. FARMER, a citizen of the United States, residing at Pittsburgh, in the county of Allegheny and 5 State of Pennsylvania, have invented new and useful Improvements in Angle-Cock Handles, of which the following is a specification.

This invention relates to angle cocks, more 10 particularly as employed in connection with fluid pressure brake equipments.

It has heretofore been proposed to provide an angle cock device having a handle adapted to lock in the open and closed positions of 15 the cock so as to prevent the accidental movement of the cock.

With the above construction, however, it is possible for an unauthorized person to turn the cock and thus render an accident 20 liable to happen, since the turning of the cock from its open to its closed position, especially near the head end of the train, prevents the brakes from being operated in the usual manner.

25 The principal object of my invention is to overcome the above difficulty.

In the accompanying drawing, Figure 1 is an elevation of an angle cock device with 30 my invention applied thereto, and Fig. 2 a plan view of the detachable handle applied to the locking member.

The invention is shown as applied to an angle cock device of the type having a self locking handle, such as disclosed in Reissue 35 Patent No. 12,574 of Inches and Hosker, dated Dec. 11, 1906, and comprising a cock body 1 and a locking member 2 pivotally mounted thereon.

According to my invention, the usual handle portion of the locking member 2 is cut off leaving a short stub end 3 and a hole 4 is drilled therein.

40 A detachable handle 5, which can be carried by the operator, is provided having an upper forked portion 6 adapted to engage outside of the flanges 7 of the locking member 2.

Beneath the forked portion 6 is a tongue

8 having a pin 9 mounted therein and adapted to engage the hole 4.

When it is desired to manipulate the cock, the handle 5 is applied, so that the pin 9 engages within the hole 4 and then the member 2 can be raised by lifting the handle so as to disengage the projection 10 from the stop 55 11 on the cock body. The cock may then be turned by operating the handle in the usual manner.

When the cock has been moved to the desired position, the handle 5 is removed and 60 the member 2 will be locked in position, by the engagement of one of the projections 10 with the adjacent stop 11.

Since the stub end 3 is short, it is difficult to move the member 2 without employing the 65 handle 5, so that an unauthorized manipulation of the cock is practically prevented.

Having now described my invention, what I claim as new, and desire to secure by Letters Patent, is:—

1. The combination with an angle cock device comprising a cock and a locking member pivotally mounted on the cock for operating the cock, of a detachable handle adapted to be applied to said member for 75 operating same.

2. The combination with an angle cock device having a member pivotally mounted thereon for operating the cock and provided with a projecting stub having a hole therethrough, of a detachable handle provided with a pin for engaging within said hole to permit the manipulation of said member by the handle.

3. The combination with an angle cock 85 device having a member pivotally mounted thereon for operating the cock and having a projecting stub and vertical flanges, of a detachable handle provided with a forked portion adapted to engage the flanges and a 90 tongue having a pin for engaging a hole in the stub.

In testimony whereof I have hereunto set my hand.

CLYDE C. FARMER.
